(57) **CLAIM**

The ornamental design for a vehicle body, as shown and described.

DESCRIPTION

FIG. 1 is a front and left side perspective view of a vehicle body embodying our new design;

FIG. 2 is a rear and right side perspective view thereof;

FIG. 3 is a right side elevation view thereof;

FIG. 4 is a left side elevation view thereof;

FIG. 5 is a front elevation view thereof;

FIG. 6 is a rear elevation view thereof;

FIG. 7 is a top plan view thereof;

FIG. 8 is a bottom plan view thereof;

FIG. 9 is a detail right side panel view thereof; and,

FIG. 10 is a detail left side panel view thereof.

The dot-dash broken lines that are immediately adjacent the claim depict the bounds of the claimed design and form no part of the claim; all of the broken lines illustrated environmental structure and depict portions of the article that form no part of the claimed design.

1 Claim, 10 Drawing Sheets
